N. MADDOX

ADJUSTABLE BORING MACHINE

Filed Aug. 6, 1925

UNITED STATES PATENT OFFICE.

NOTLEY MADDOX, OF LOS ANGELES, CALIFORNIA.

ADJUSTABLE BORING MACHINE.

Application filed August 6, 1925. Serial No. 48,581.

My invention relates to improvements in boring machines. Certain of the features contained therein make it also classifiable with drilling machines.

5 These features are prominent over the art, the principal ones being pointed out while others will be quite obvious to those skilled in the art to which this invention appertains.

10 The principal features inculcated therein are, namely:

First: A boring bar adapted to have mounted thereupon different kinds and sizes of drills, augers, bits and various other 15 kinds of similar tools used for drilling into rock, earth and wood.

Second: The device is automatic, adjustable and portable.

Third: It is operative in a plane throughout 20 an angle of 120° of a circle.

Fourth: It is engine driven and hand operated.

Fifth: It is simple to construct and is efficient in accomplishing the work for 25 which it is intended.

In addition to these features as outlined many others are apparent, a novel one being its use for drilling holes in stumps, these holes being drilled at an angle so as to converge in forming a pocket having a central hole opening therefrom out of the top of the stump, then filling the holes with distillate or the like and allowed to stand.

Later, by the application of a blow torch, 35 means of which have been provided for supplying the air in connection with the boring device, suggests a simple, cheap and less laborious method for removing stumps by burning them, since this device is pri-

40 marily designed to be used in connection with an adjustable truck, to which is applied an adjustable sawing machine, for which Letters Patent have been allowed and are pending, as well as the adjustable bor-

45 ing machine, and the objects for which it is intended will readily portray the reason for wishing to combine it as a useful auxiliary with the adjustable sawing machine with which it is associated.

50 Referring to the drawing and the following description for a clear and concise revelation of the same:

Figure 1 is a perspective view of the boring machine mounted upon an adjustable 55 and portable truck, connected to a source of power and an air compressor.

Figure 2 is a view taken on the line 2—2 of Figure 1.

Figure 3 is a view taken on the line 3—3 of Figure 1.

In Figure 1, (1) is an engine of any preferred type or make, mounted upon a wood platform (32) having a common engine shaft (28) upon the extreme ends of which are mounted drive sprockets (27) and (2).

60 The drive sprocket (2) is connected to a driven sprocket (4) mounted upon a pinion shaft (54) by a sprocket chain (3).

Upon the pinion shaft (54) is a pinion gear (53) keyed thereto and which functions with a bevel gear (52) in rotating boring bar (45) and a bevel gear (51) in reversing the rotation of boring tool (56) fastened to boring bar (45) by a pin (57), the boring bar (45) extending through 75 sleeve (55) having a square slot (50) upon which the bevel gears (51) and (52) are keyed.

The sleeve (55) contains a groove (47) 80 into which is extended an operating handle 48 hingedly fastened at (49). The sleeve (55) having a friction fit upon the boring bar (45) extending through the square slot (50) readily holds the bevel gears (51) and (52) in mesh with pinion gear (53) upon 85 the shifting of sleeve (55) by operating handle (48), throwing either combination in gear.

The sleeve (55) and pinion shaft (54) are rotatively mounted within a split housing (15) and angularly adjustable in a plane throughout an angle of 120 degrees of a circle, said housing containing a slotted portion for the reception of the pinion gear (53) and bevel gears (51) and (52).

90 The housing (15) is made in two halves and bolted together by bolts inserted in holes (16), the ends (6) of said halves are made semi-circumferential, so that when the two halves are bolted together they form 95 a shaft, which is carried and is rotatable in the side top plate member (9) of the supporting framework fastened to the main truck frame.

Fastened to the housing (15) and extending therefrom parallel with the boring bar (45) are two racks (17) machined into an end bearing (46) containing a hole through which the boring bar (45) is extended.

100 Upon the racks (17) is mounted a movable carriage (39) by means of which the boring tool is fed into and out of the work.

Comprising the carriage (39) which is also a split member and bolted together at bolt holes (40) are pinion gears 18^a and 20^b mounted upon pinion shafts (19) and (21) and meshing with racks (17).

5 A set collar (43) having a set screw (44) holds the boring bar (45) in rigid position by the set collar being contained in a slotted portion on the lower part of the carriage (39).

10 On the outside of the carriage (39) and upon pinion shafts (19) and (21) are mounted pinion gears (18) and (20); which mesh together, the adjustability of the carriage (39) within the racks (17), being governable by a hand wheel (36) having a handle (38) and keyed to pinion shaft (21).

15 By rotating the hand wheel (36) in a counter-clockwise direction, the boring tool will be fed into the work and upon the rotation of the handwheel in a clockwise direction the boring tool will be displaced from the work.

20 The racks (17) are made of a dependable length so that any ordinary depth hole may be made; however, if a greater depth hole is desired a coupling may be added upon the boring end of the boring bar (45).

25 The carriage and racks mounted upon the housing (15) and angularly adjustable, are held in the various angles desired by ratchet (14) and a pawl (12), the ratchet being interposed between the housing (15) and top side frame member of supporting frame, 30 while the pawl (12), hinged on a pin (11), is held engageably thereto by a tension spring (13).

35 The adjustable portion of the boring machine is carried upon an adjustable truck by means of a framework consisting of two angle iron upright frame members (5) bent so as to have their horizontal legs engageable to the angle iron side frame members (42) of the main truck frame by bolts (31) and wing nuts (30).

40 Transversely connecting the upright members (5) are top side frame members (9) bolted at 9^b and bottom side frame members (10) riveted at 10^a.

45 Additional holes (8) are provided in the upright members (5) for adjustability of revolvable boring machine supported by said framework.

50 Gusset plates (7) riveted to angle iron uprights (5) at 7^a insure a more rigid construction of the framework when applied to the adjustable truck.

55 This truck consists of angle iron side frame members (42) as stated before and has movably mounted thereon a wooden platform (32) having a top platform plate member (29) and a bottom platform plate member (35).

60 The ends of the platform plate members (29) and (35) are bolted together at (37)

and rollers (33) and (34) impinge upon the sides and bottom of angle iron frame (42).

65 This structure of adjustable truck is fully described and claimed in Patent #1,547,770.

70 Auxiliary connected to the engine (1) and compounded to boring machine is an air compressor (23) mounted upon a base (24), the air compressor (23) having a nozzle (22) to which is applicable an air hose which may be connected to a blow torch for providing 75 a more violent flame in the removal of stumps by burning; this being one of the principal objects, as stated before, for which this invention is intended.

75 The shaft (25) of the air compressor is 80 connected to a sprocket (27) fastened on the engine shaft (28) by a sprocket chain 27^a.

85 It will be obvious that certain modifications may be necessary upon the adaptation of the invention to the several purposes for which it is intended and the modifications will be allowable so long as no marked departure is made from the features as set forth in the following claims appended hereunto.

90 Having thus fully described my invention. I claim:

1. An adjustable boring machine comprising a framework consisting of two parallel U-shaped upright members transversely connected by top and bottom side frame members, the top side frame members of said framework supporting the trunnions of a split housing, rotatively supporting two parallel upright racks terminating into an end bearing; a carriage supported by said racks and longitudinally adjustable between aforesaid housing and end bearing; a boring bar and tool, the bar of said boring bar and tool of extendable length being intermediate- 100 ly positioned in a plane between and in parallel relation to aforementioned parallel racks and adapted to be raised and lowered through engagement to aforesaid carriage, 110 substantially as herein set forth.

105 2. In an adjustable boring machine of the character described, a rotatable boring bar and tool, two parallel racks carried by a rotatable housing and having their projecting ends terminating in an end bearing and supporting in alignment therewith said boring bar and tool; a carriage supported and longitudinally adjustable in a plane with said parallel racks, the said boring bar extending through said carriage and end bearing being adapted to be fed into the work by a hand wheel operatively connected to aforesaid racks by pinions meshing with said racks and supported in said carriage upon pinion shafts carrying companion gears, whereby the engagement of said companion gears to aforementioned hand wheel the aforesaid boring bar and tool is fed into and out of the work, substantially as set forth.

115 120 125 NOTLEY MADDOX.
